EARTH TREATING MACHINE

Manuel T. Barela, 715 Elm St.,
Fort Collins, Colo. 80521

Filed Nov. 10, 1972, Ser. No. 305,497

Term of patent 14 years

Int. Cl. D15—03, 04

U.S. Cl. D35—2 A

FIG. 1

FIG. 2

FIG. 3

FIG. 4

FIG. 5

FIG. 6

FIG. 1 is a perspective view of the earth treating machine showing my new design;

FIG. 2 is a side view thereof, the opposite being a mirror image thereof;

FIG. 3 is a front elevation thereof;

FIG. 4 is a top plan thereof;

FIG. 5 is a rear elevation thereof; and,

FIG. 6 is a bottom plan view thereof.

I claim:

The ornamental design for the earth treating machine, as shown and described.
